UNITED STATES PATENT OFFICE.

GEORGE A. LEY, OF SOUTH BEND, INDIANA.

PHOTOGRAPHIC-PRINTING MACHINE.

984,096.

Specification of Letters Patent. Patented Feb. 14, 1911.

Application filed October 18, 1909. Serial No. 523,323.

To all whom it may concern:

Be it known that I, GEORGE A. LEY, a citizen of the United States, residing at South Bend, in the county of St. Joseph and State of Indiana, have invented certain new and useful Improvements in Photographic-Printing Machines, of which the following is a specification.

My invention relates to improvements in photographic printing machines.

The primary object of my invention is to provide a simple and effective means for holding the pressure-back in contact with the sensitized paper and negative, and to lock the same in position.

A further object resides in the provision of easily operated means for locking the pressure-back in operative position, so as to obviate the necessity of using manual effort to so hold the pressure-back during the printing operation.

A further object resides in the provision of locking means for pressure-backs of photographic printing machines, which is simple and positive in operation, and capable of manipulation by a single movement to lock or unlock the same, in order that great speed may be obtained by the operator in placing the sensitized paper in the machine and taking the exposed paper therefrom.

With this and other objects in view, the present invention consists of the construction hereinafter more fully described, illustrated in the accompanying drawings, and particularly pointed out in the claims, it being understood that changes may be made in the form, proportion, size and minor details without departing from the spirit or sacrificing any of the advantages of the invention.

In the drawings:—Figure 1 is a perspective view, showing a complete machine with the pressure-back out of operative position. Fig. 2 is a perspective view showing the pressure-back in operative position. Fig. 3 is a fragmentary perspective view showing the means for locking the pressure-back in operative position in detached relation. Fig. 4 is a fragmentary side view showing the pressure-bar and pressure-back in operative relation with the locking means in operative position, the dotted lines showing the manner of raising the outer section of the pressure bar to detach or unlock the same. Fig. 5 is an enlarged side detached view of a spring catch which forms one of

the means for locking the pressure bar in operative position.

Referring now more particularly to the accompanying drawings, 1 represents a box, 60 which may be of any suitable form, and 2 indicates electric lamps disposed within the box and connected in circuit and controlled by means of a switch (not shown) which is normally held open by any suitable means. 65 A pin 3 is operatively connected to said switch and projects through the casing of the box. When this pin is depressed by a pressure-bar, the function of which will be hereinafter explained, it switches on the 70 lights. The switch is of a type which will automatically open when pressure on the pin is released.

4 is a rectangular frame provided with shoulders 5 to support a negative, and having an open inner side in communication with the light chamber in order to expose the negative to the light. The upper side of said frame is also open, and hinged at 6 is a two part pressure back consisting of the 80 sections 7 and 8 hinged together in any suitable manner. This back is provided with a handle 9 for use in opening and closing the same, the same being shown open in Fig. 1 and closed in Fig. 2. A pressure-bar is hinged to the frame by means of any suitable hinge 10, said bar consisting of two parts 11 and 12, connected together by a spring hinge 13, the tension of the spring on said hinge tending to normally hold the two 90 parts of the bar in alinement, as shown in full lines in Fig. 4. Secured to the under side of the part 12 of the pressure bar is an L-shaped metal member 14 which is adapted to contact with the beveled upper edge 15 95 of the catch 16, which is pivoted at 17 and normally held at its extreme outward movement, which is limited by a keeper 18, by a coil spring 19 disposed between the catch and the plate 20. Secured to the under side 100 of the pressure bar member 12 are two plate springs 21 and 22, adapted to exert a downward pressure upon the pressure-back when the bar is forced into locked position. The plate 20 with which are integrally formed the 105 keeper 18 and the laterally extending arms 23, to which the spring catch 16 is pivoted, is secured to the side of the frame 4 by screws or any other suitable fastening means.

The reference character 10' indicates a 110 stop to limit the outward swing of the part 11 of the pressure bar, so that the bar will

be held in a convenient position for manipulation, slightly out of the vertical. The stop 10' also protects the hinged end from being broken because the pressure bar can-
5 not be accidentally dropped when swung outwardly to the extent of breaking the hinge 10.

24 represents a plug and its wire connection with the lamps in the case, adapted to
10 be attached to a corresponding socket on an electric circuit to supply current for the lamps.

In operation, the operator of the machine places the negative from which the prints
15 are to be made in the frame, a sheet of sensitized paper is next placed upon the negative and the pressure back is closed. The pressure-bar is next lowered and forced down until the locking member
20 on the under side thereof forces the spring catch inwardly and passes the offset thereon, when the catch springs back into its normal position, and securely locks the bar in place, as clearly shown in Fig. 4. The springs 21
25 and 22 on the pressure bar being under tension when the bar is locked in position, the latter imparts a downward pressure upon the pressure-back and thus produces a proper contact between the print and the
30 negative. After the print has been exposed the requisite length of time, the pressure bar is released by simply exerting pressure upwardly upon the outer member thereof, which will cause same to break at the point
35 at which it is hinged, as shown in dotted lines Fig. 4, and the unlocking thereof is easily and quickly accomplished, and with a minimum amount of exertion and manipulation.
40 In order to permit the pressure-back to be raised or lowered in a single operation, the same is connected with the pressure-bar by a double hinge 25 as shown in Fig. 4. This connection also permits the section 8
45 of the pressure-back to be raised a considerable distance before the section 7 starts to

raise, and conversely when the same is lowered, which enables the operator to properly position the print paper upon the negative and grip the paper with the section 7 50 before the other section is finally lowered.

What is claimed is:—

1. In a photographic printing machine, the combination with a box having a light compartment and a source of light therein, 55 a negative receiving frame secured to the box and communicating with the light compartment, a pressure-back hingedly connected to said frame, a locking element on said frame, a two-part pressure bar hingedly secured to said frame, and a locking element carried by one part of said bar for coöperative engagement with the aforesaid locking element, said parts of the bar being hinged at a point adjacent the locking element of 60 the box whereby the locking element of the bar may be released therefrom by elevating the part of the bar to which the bar locking element is secured.

2. In a photographic printing machine, 70 the combination with a box having a light compartment and a source of light therein, a negative receiving frame secured to the box and communicating with the light compartment, a pressure-back hingedly connected to said frame, a locking element on said frame, and a two-part pressure bar hingedly secured to said frame, said bar having its parts hingedly connected together and one part carrying means for co- 75 operative engagement with said locking element and projecting beyond the box and said locking element, whereby the projecting part may be elevated to release the bar from the locking element. 80

In testimony whereof I affix my signature, in presence of two witnesses.

GEORGE A. LEY.
